UNITED STATES PATENT OFFICE.

HARLOWE EDSON TRUMBULL, OF AMESBURY, MASSACHUSETTS.

RIVETING-MACHINE.

1,352,851.

Specification of Letters Patent. Patented Sept. 14, 1920.

Application filed December 13, 1918. Serial No. 267,552.

To all whom it may concern:

Be it known that I, HARLOWE E. TRUMBULL, a citizen of the United States of America, and a resident of Amesbury, in the county 5 of Essex and Commonwealth of Massachusetts, have invented certain new and useful Improvements in Riveting-Machines, of which the following is a specification.

This invention relates to riveting machines and has for its object the production 10 of a portable device of this character in which a plurality of blanks are intermittently and successively fed through the discharge orifice and in which the head of each 15 blank is swaged or shaped as delivered from said orifice to give final shape thereto and provide a support therefor while the opposite end of the blank is being upset.

The invention consists in a manually supported casing provided with a heating chamber through which are fed a plurality of blanks, preferably in a string, combined with devices for cutting off the foremost blank and simultaneously swaging or shaping a 25 head thereon to give final shape thereto and provide a support therefor while the opposite end of the blank is being upset.

The invention further consists of certain 30 novel features of construction and combination of parts which will be readily understood by reference to the description of the drawings and to the claims to be hereinafter given.

For the purpose of illustrating the invention, one preferred form thereof is illustrated in the drawings, this form having been found to give satisfactory and reliable results, although it is to be understood that the various instrumentalities of which the 40 invention consists can be variously arranged and organized, and that the invention is not limited to the precise arrangement and organization of the instrumentalities as herein shown and described, except as required by 45 the scope of the appended claims.

Of the drawings—

Figure 1 represents a plan of a machine embodying the features of the present invention.

50 Fig. 2 represents a front elevation of the same with the various parts in position preparatory to feeding the blanks.

Fig. 3 represents a side elevation of the same.

55 Fig. 4 represents a front elevation with

the parts in position after the blanks have been fed.

Fig. 5 represents a side elevation of the same with the parts in the position shown in Fig. 4. 60

Fig. 6 represents a vertical section of the same on line 6, 6, on Figs. 2 and 4.

Fig. 7 represents a perspective of the devices for cutting off and heading the blanks, the parts being shown separated to permit 65 the feeding of a new blank thereto.

Fig. 8 represents a similar view with the parts closed after a blank has been severed from the string of blanks, and

Fig. 9 represents an elevation of a string 70 of blanks designed to be used in said machine.

Similar characters designate like parts throughout the several figures of the drawings. 75

In the drawings, 10 is a cylindrical casing having a plate 11 secured to the upper end thereof by means of a plurality of screws 12. The lower end of the casing 10 has secured thereto a closing cap 13 provided with a 80 tubular extension 14. Within the casing 10 is a heating chamber 15 having an exhaust passage 16 extending therefrom through a handle 17 formed upon the casing 10.

The casing 10 is provided with an ear 18 85 extending longitudinally of one side thereof, said ear having passages 19 and 20 extending therethrough, through which air and gas may be admitted through the pipes 21 and 22 when the valves 23 and 24 are open. 90

The passages 18 and 19 communicate with a single passage 25 in which the air and gas is adapted to mix, the opposite ends of said passage being provided with a burner 26 through which the combustible mixture is 95 adapted to be ejected.

When this combustible mixture is ignited, the heating chamber 15 will be thoroughly heated and this heat will be transmitted to any metal object admitted to said chamber 15. 100

Surrounding the upper end of the casing 10 is a cage composed of two end plates 27 each of which has rigidly secured thereto a pair of bars 28, the outer ends of which have reduced shanks 29 extending through openings 30 in the opposite end plate. 105

Beneath the top plate 11 and in contact therewith are two cutting members 31, each of these cutting members being dovetailed 110

in and secured to an end plate 27 by a screw 32.

The outer ends of the cutting members 31 are adapted to be moved into contact with each other as indicated in Fig. 8 to cut off a blank and give final shape to the head thereof, said cutting member being adapted to provide a support for said head while the opposite end of the blank is being upset.

10 The outer faces of the coacting ends of these cutting members 31 are provided with coacting recesses 33 so shaped as to form a head on the ejected blank when the cutting members 31 have been moved toward each other.

15 The upper and lower bars 28 on one side of the cage, are each provided with a laterally extending trunnion 34, said trunnions extending through slots 35 in an operating lever 36 pivoted at 37 to the casing 10.

20 The lever 36 is provided with a handle 38 by which said lever may be moved about the pivot 37 to move the cutting members 31 into the position shown in Fig. 8 when it is desired to cut off a blank and swage or shape the head thereof or separate said cutting members as shown in Fig. 7 when it is desired to feed a new blank through the discharge orifice 39 in the plate 11.

25 The lever 36 is provided with a lateral projection 40 having formed therein a cam slot 41, and in said cam slot 41 is positioned a pin 42 extending laterally from the lower end of one arm of a lever 43 pivoted to the casing 10 at 44.

30 The other arm of said lever 43 is provided with an opening 45 therethrough to receive one end of a connecting link 46, the opposite end of which is pivotally connected to the outer end of the operating lever 47 of the feeding mechanism.

35 The tubular extension 14 of the cap 13 is provided with a tubular boss 48 extending into the cylindrical heating chamber 15 and fitting the inner wall thereof as indicated in Fig. 6 of the drawings.

40 Fixedly secured in the outer end of the tubular extension 14 is a cylindrical member 49 having a similar member 50 in alignment therewith extending into the heating chamber 15 as indicated in Fig. 6 of the drawings.

45 Interposed between the outer wall of the heating chamber 15 and the inner wall of the casing 10 is a mass of asbestos or similar material which prevents the heat generated in the heating chamber 15 from being transmitted to the outer surface of the casing 10.

50 When the machine is in use, a string of blanks 51, as indicated in Fig. 9, is inserted into the cylindrical members 49, 50 and this string of blanks is intermittently fed endwise through the members 49, 50 and the

heating chamber 15 to the cutting off and swaging or shaping devices 31, 33.

55 As these blanks are fed through the heating chamber, the heat from the burner 26 will bring the blanks to a white heat and into such condition that the foremost blank may be readily severed from the remaining blanks and the head thereof simultaneously swaged or shaped.

60 The cylindrical member 49 and the tubular extension 14 has a slot 52 cut therethrough to receive the feeding claw 53, pivoted at 54 to the bell-crank lever 47.

65 The heel 55 of the feeding claw 53 is held normally in contact with the projection 56 by means of the spring 57.

70 When the cutters 31 are in the position indicated in Fig. 8 of the drawings, the lever 36 is in the position shown in Fig. 2 of the drawings.

75 When it is desired to feed another blank through the discharge orifice 39, the lever 36 is moved in the direction of the arrow *a* into the position shown in Fig. 4 of the drawings.

80 During the initial movement of the lever 36, the cutters 31 will be moved away from each other and by the time these cutters have been sufficiently separated, the shoulder at the outer end of the slot 41 will come into contact with the pin 42 and move the lever 43 about its pivot 44 thus producing the feeding of the string of blanks. The feeding claw 53 normally is in the position shown in Fig. 3 of the drawings but when the upper arm of the operating lever 47 is forced downwardly by the link 46 into the position shown in Fig. 5 of the drawings, the claw will be moved forward across the bore of the cylindrical member 49. During the forward movement of the claw 53 it will engage with a head 58 of a blank 51 and will feed the string of blanks forward a distance sufficient to bring the foremost blank into a position where it may be severed from the string of blanks upon the return movement of the lever 36 in a direction opposite to that indicated by the arrow *a* in Fig. 2 of the drawings.

85 The casing 10 is provided with a removable cap 59 which closes a passage 60 to the heating chamber 15, said passage being adapted for use in lighting the combustible mixture being ejected from the burner 26 when it is desired to use the machine.

90 In the operation of the machine the cap 59 is removed, the valves 23, 24 opened to admit a combustible mixture to the burner 26 and this combustible mixture is ignited by a lighter inserted into the passage 60.

95 A string of blanks 51, 58 is then inserted into the tubular extension 14 far enough to permit the feeding claw 53 to coact with the heads 58 thereof.

100 By manipulating the handle 38, the string 130

of blanks may be fed into the heating chamber 15 passing through the flame from the burner 26.

During the passage of the blanks through 5 the heating chamber 15, the said blanks are heated to a white heat. When the operator considers that the blanks have been heated sufficiently the handle 38 is operated to separate the cutting members 31. When 10 these cutting members have been fully separated the string of blanks are fed forward so that the foremost blank of said string will be ejected from the machine into the opening in the plates to be riveted.

15 When the foremost blank has been inserted in said opening, the handle 38 is then operated to move the cutting members 31 toward each other, this movement severing the foremost blank from the string of blanks 20 and simultaneously swaging the head thereof, the shape of the head conforming to the shape of the depressions 33 in the outer faces of the cutting members 31.

To drive and head another rivet, the operation is repeated.

It is believed that the operation and many advantages of this invention will be fully understood without further description.

Having thus described my invention, I 30 claim—

1. In a machine of the class described, the combination of a manually supported heater; means for feeding a partially headed blank through said heater; and a device 35 for swaging the head on said blank to give final shape thereto.

2. In a machine of the class described, the combination of a heater; a supporting handle therefor; means for feeding a column of 40 partially headed blanks through said heater; and a device for swaging the head on each foremost blank to give final shape to said head and provide a support therefor while the opposite end of the blank is being upset.

45 3. In a machine of the class described, the combination of a heater; a supporting handle therefor; means for feeding a string of partially headed blanks through said heater; means for severing the foremost blank from 50 said string; and means for swaging the head on said severed blank to give final shape to said head and provide a support therefor while the opposite end of the blank is being upset.

55 4. In a machine of the class described, the combination of a heater; a supporting handle therefor; means for feeding partially headed blanks through said heater; means for swaging the head on the foremost blank 60 to give final shape to said head and provide a support therefor while the opposite end of the blank is being upset; and a single manually operated device for actuating said feeding and swaging means.

65 5. In a machine of the class described, the

combination of a heater; a supporting handle therefor; a tubular member extending partially through said heater; means for feeding a string of partially headed blanks through said tubular member and heater; a cutting off device; and means for actuating said cutting off device.

6. In a machine of the class described, the combination of a casing provided with a heating chamber; a supporting handle therefor; a tubular member extending partially through said heater; a burner in said heater between the end of said tubular member and the delivery end of said machine; means for supplying a combustible gas to said burner; 75 means for feeding a partially headed blank through said tubular member into said heating chamber and subjecting it to the heat from said burner; and a device for swaging the head on said blank to give final 80 shape to said head and provide a support therefor while the opposite end of the blank is being upset.

7. In a machine of the class described, the combination of a manually supported casing 90 provided with a heating chamber; means for feeding a column of partially headed blanks through said heating chamber and subjecting said blanks in their movement through said heater to heat therein of a gradually 95 increasing intensity; and a device for swaging the head on each foremost blank to give final shape to said head and provide a support therefor while the opposite end of the blank is being upset.

8. In a machine of the class described, the combination of a manually supported heater having a centrally disposed cylindrical heating chamber; means for regulating the heat in said heater; means for feeding a string of 100 partially headed blanks through the center of said heater from end to end; means for severing the foremost blank from said string; and means for simultaneously swaging the head on said severed blank to give 110 final shape to said head and form a support therefor while the opposite end of the blank is being upset.

9. In a machine of the class described, the combination of a casing having a centrally 115 disposed cylindrical heating chamber; means for feeding partially headed blanks through said heating chamber from end to end; co-acting reciprocating members beyond the outer end of the heating chamber for swaging the head on the foremost blank to give final shape to said head and provide a support therefor while the opposite end of the blank is being upset; and means for actuating said feeding and swaging means.

10. In a machine of the class described, the combination of a manually supported casing having a centrally disposed cylindrical heating chamber; a tubular member extending into said heating chamber; means 125

for feeding a string of partially headed blanks through said tubular member into said heating chamber; coacting reciprocating members for cutting off a single blank 5 at the outlet from said heating chamber; and means for actuating said cutting members at a predetermined time.

11. In a machine of the class described, the combination of a heating chamber; 10 means for feeding a string of partially headed blanks therethrough; two reciprocating members at the discharge end of said machine for cutting off the foremost blank; a pivoted lever for operating said 15 reciprocating members provided with a slotted extension; a device for feeding blanks through said heating chamber between said reciprocating members; a bell-crank lever one arm of which is provided 20 with a pin positioned in the slot of said extension; and a link between the other arm of said lever and said feeding device.

12. In a machine of the class described, the combination of a heating chamber; 25 means for feeding a string of partially headed blanks therethrough; two reciprocating members at the discharge end of said machine for cutting off the foremost blank and provided with coacting depressions 30 adapted to head a rivet; a pivoted lever for

operating said reciprocating members provided with a slotted extension; a device for feeding blanks through said heating chamber between said reciprocating members; a bell-crank lever one arm of which is provided 35 with a pin positioned in the slot of said extension; and a link between the other arm of said lever and said feeding device.

13. In a machine of the class described, the combination of a portable casing provided with a centrally disposed cylindrical heating chamber and aligned inlet and outlet passages communicating with and in alignment with said chamber; means for feeding a partially headed blank through 40 said inlet passage into said heating chamber and subjecting it to the heat therein; and means for giving a final shape to said head when delivered from said heating chamber, said shaping means being adapted 45 to provide a support for the finished head while the opposite end of said blank is being 50 upset.

Signed by me at 4. Post Office Square, Boston, Mass., this 3rd day of December, 55 1918.

HARLOWE EDSON TRUMBULL.
